DESIGN FOR A BATHING SUIT OR SIMILAR ARTICLE

Alex A. Mitchell, Portland, Oreg.

Application November 9, 1942, Serial No. 108,729

Term of patent 7 years

(Cl. D3—17)

To all whom it may concern:

Be it known that I, Alex A. Mitchell, a citizen of the United States residing at Portland, in the county of Multnomah and State of Oregon, have invented a new, original, and ornamental Design for a Bathing Suit or Similar Article, of which the following is a specification, reference being had to the accompanying drawing, forming a part thereof.

Fig. 1 is a front perspective view of a bathing suit showing my new design;

Fig. 2 is a rear perspective view thereof;

Fig. 3 is a plan view thereof; and

Fig. 4 is a side perspective view of the bathing suit shown in Fig. 1.

I claim:

The ornamental design for a bathing suit or similar article, as shown.

ALEX A. MITCHELL.
